UNITED STATES PATENT OFFICE.

ALOYS HAGE, OF HILDESHEIM, GERMANY.

VEHICLE.

No. 909,402.

Specification of Letters Patent. Patented Jan. 12, 1909.

Application filed October 5, 1908. Serial No. 456,212.

To all whom it may concern:

Be it known that I, ALOYS HAGE, residing at Hildesheim, in the Province of Hanover, Prussia, Germany, have invented certain new and useful Improvements in or Relating to Vehicles; and I do hereby declare the following to be a full, clear, and exact description of the invention, such as will enable others skilled in the art to which it appertains to make and use the same.

This invention relates to a steering connection between the fore and back portions of four-wheel vehicles of any kind.

The object of this steering connection is to insure a great mobility in all directions between the two parts of the vehicle and at the same time to offer a certain resistance to the movements of both parts relatively to each other, except as regards rotation about the pivot pin in a horizontal plane, and to moderate or prevent free oscillations of the separate parts. In loading the vehicle it is therefore unnecessary to pay special attention to equilibrium, as even if equilibrium be not obtained in one or the other part, the smooth traveling of the vehicle is not affected to any considerable extent.

Owing to this steering connection, it is possible to drive on rough roads without damaging either the vehicle or the horses by the movements of the pole. This latter is smoothly guided and is supported in every position by the steering connection which can be made in the form of an easily detachable coupling, so that the two parts of the vehicle can be easily disconnected.

Several constructions of the steering connection according to the present invention are illustrated by way of example in the accompanying drawings, in which—

Figure 1 is a plan, Fig. 2 a vertical longitudinal section, and Fig. 3 a cross section on line A—B of Fig. 2 of one construction. Fig. 4 is a plan, Fig. 5 a vertical longitudinal section, and Fig. 6 a cross-section on line C—D of Fig. 5 of a second construction. Fig. 7 is a vertical longitudinal section through a third construction, and Fig. 8 a corresponding plan.

In the construction shown in Figs. 1 to 3, the steering connection consists of a member 1 which is made so as to be secured to one of the vehicle parts (in this case it has the shape of a fork) and of a member 2 which is made in the shape of a foot of a pole for detachably mounting it on the other carriage

part, but it can also be made of any other shape. The member 1 is formed with a frame 3 provided at 4 with apertures for pins 5 of a universal coupling joint. This joint 60 consists of an eye shaped central part 6 to which are secured the pins 5, and through the aperture of which is passed a bolt 20 forming the pivot pin of the joint.

To the part 2 is secured a box 7 closed by a cover 9, forming a circular rim and affording guidance to the vertical steering bolt 8, so that the stem of the bolt can slide in the cover. A nut 11, mounted on the bottom screw-threaded portion 10 and being of cylindrical outside shape, can also slide in the guide sleeve 12 mounted on the bottom of the box. The bolt 8 terminates at the top in a fork 13 surrounding the central portion of the universal joint, so that the bolt 20 75 passes through the fork portion 13.

In the box 7 is mounted any desired number of springs 14, 15, which on the one hand rest against the cover 9, and on the other hand against the disk or washer 16 carried by the nut 11, so that the bolt is strongly pulled down by the said springs. The parts 17 17' of the frame, arranged transversely of the longitudinal direction of the steering connection, are rounded off at the bottom, 85 that is to say, cylindrically about the axis of the bolt 20, as shown in Fig. 3, and have also a short curvature (Fig. 2) at 18, 19, so that on the one hand the two main parts of the connection can rotate about the bolt 20 90 (Fig. 3) and on the other hand, move up and down in the direction of the arrows I and II (Fig. 2). During the latter movement, the frame rests only with its transverse part on the support, in such manner that during the movement in the direction of the arrow I, the frame rests only at 19 on the upper side of the cover, while during the movement in the direction of the arrow II, it rests at 18. Both when moving in the direction of the arrow I and in the direction of the arrow II, during these vertical movements, the springs 14 and 15 are compressed, as the universal joint and, therefore, the bolt 8, are raised, whether the frame be resting only at 18 or 105 at 19.

The transverse portions 17 17' of the frame are not at equal distance from the axis of the bolt 8, the portion 17' being nearer to the said axis than 17, so that the weight of the 110 pole is equalized. The springs act then on a larger lever arm, that is to say, they offer

approximately the same resistance to a downward movement and to an upward movement, in spite of the weight of the pole.

The box 7 is not an essential part of the steering connection, it being provided merely for protecting the springs, it being only necessary that the bolt 8 should be securely guided. It is, therefore, merely necessary to have the covering disk 9 with some connecting part for the back carriage. The position of the box or of the springs is also immaterial, as they can be arranged either as shown, below the universal joint 5, 20, or above the same. The universal joint could also be replaced by a ball and socket joint.

The construction shown in Figs. 4 to 7 differs from the construction already described by the fact that the rotation of the carriage parts about the longitudinal axis no longer takes place, and that it no longer takes place only about the bolt 20, but on the contrary a separate bolt 21 is provided firmly secured to the frame 3, 17. The said bolt 21 is rotatably mounted in the frame 22 of one vehicle part (fore-carriage or back-carriage) and is guided in a longitudinally adjustable manner, for which purpose two perforated fixed transverse bridges 23, 24 are arranged between the parts 22, the bolt passing through the said bridges. The said bolt is provided at 25 with a screw-thread on which is screwed the nut 26. Moreover, round the bolt is placed a helical pressure spring 27 resting on the one hand against the nut 26, and on the other hand against the transverse bridge 23. 28 is a stop secured to the frame 3, 17, against the roof-shaped upper portion 29 of which comes to rest the bottom of the transverse bridge when the fore-carriage shifts relatively to the back carriage, so that the said movement is limited. This movement of the bolt in the frame can be obtained in any other desired manner, for instance by means of a spring key secured to the bolt 21, and a wide groove in the transverse bridge 24.

The two vehicle parts can, therefore, turn relatively to each other about the axis of the bolt 21, but they can also change their distance from each other by compressing the spring 27, whereby suddenly produced traction efforts are transmitted to the other vehicle part in a much smoother manner, and vice-versa, the starting is effected gradually, that is to say, there is less strain on the animals. The device shown in Figs. 4 to 6 can also be combined with that in Figs. 1 to 3, so that a movement can take place simultaneously, both in the universal joint about the steering bolt, that is to say, about the pivot pin 20, and about the bolt 23.

Figs. 7 and 8 show a simplified construction of the invention described. The bolt 20 of Figs. 1 to 6 is omitted in this construction. The turning of the two vehicle parts round their longitudinal axis takes place

only about the bolt or pin 21, and instead of a frame 3, there is a member 30 rotatably connected to the head 13 of the steering bolt 8 by means of a pin 31 arranged transversely of the longitudinal axis of the vehicle. The 70 said member 30 rests by means of surfaces 18 and 19 on the annular surface formed by the cover 9 of the spring box 7. In this construction the member 30 is hollow, so that the bolt head 13 is not bifurcated. The 75 member 30 can, however, be also made solid, and the bolt head bifurcated without the working being adversely affected. Another modification of this construction consists in the box 7 being made in one piece with the 80 cover 9 and completely open at the bottom. The nut 11 is provided with a wide flange-like disk 32 guided with its outer edge in the hollow space of the box 7. It is immaterial what kind of springs are used, whether steel, 85 gun-metal or rubber, whether tension or compression springs, helical or leaf-springs etc. By means of this steering connection, the fore-carriage is connected to the back carriage in a secure manner, and the steerability insured even on very rough roads, and with the vehicle parts loaded in an irregular manner. The vehicle parts can bend relatively to each other in passing over ditches and raised portions of the road, whatever be 90 the steering position in which they are. This bending does not take place without any resistance, but is braked, so that there are no free oscillating movements of the fore-carriage with the pole, that is to say, the latter 95 does not strike the animals. This braking of the vertical movements of the vehicle parts always takes place in the same way, whether the carriage is traveling in a straight line, bearing to the left or to the right, or 100 turning round.

What I claim is:

1. The combination, with a draft-member provided with a plate, of a spring-pressed pivot-pin slidable longitudinally in and also 110 revoluble in the said plate, a second draft-member provided with projections which bear on the said plate on opposite sides of the said pin, and a connection between the last said draft-member and the said pivot-pin 115 which permits the last said draft-member to move pivotally in a vertical plane.

2. The combination, with a draft-member provided with a plate, of a spring-pressed pivot-pin slidable longitudinally in and also 120 revoluble in the said plate, a second draft-member provided with projections which bear on the said plate on opposite sides of the said pin, and a universal joint connection between the last said draft-member and the said pin which permits the last said draft-member to move pivotally in a vertical plane and also to oscillate upon a longitudinal axis.

3. The combination, with a draft-member 130

provided with a plate, of a spring-pressed pivot-pin slidable longitudinally in and also revoluble in the said plate, a second draft-member provided with projections which bear on the said plate on opposite sides of the said pin, a connection between the last said draft-member and the said pin which permits the last said draft-member to move pivotally in a vertical plane, and a spring-controlled frame pivotally connected with the last said draft-member and free to oscillate on a longitudinal axis.

4. The combination, with a draft-member provided with a plate, of a spring-pressed pivot-pin slidable longitudinally in and also revoluble in the said plate, a second draft-member provided with projections which bear on the said plate on opposite sides of the said pin, said projections being arranged at different distances from the said pin to balance the normal load on the respective draft members, and a connection between

the last said draft-member and the said pin which permits the last said draft-member to move pivotally in a vertical plane. 25

5. The combination, with a draft-member provided with a plate and having a guide under the said plate, of a revoluble pin having a projection on its lower end and slidable longitudinally in the said plate and guide, a spring interposed between the said plate and projection, a second draft-member provided with projections which bear on the said plate on opposite sides of the said pin, and a connection between the last said draft-member and the said pin which permits the last said draft-member to move pivotally in a vertical plane. 30 35

In testimony whereof I affix my signature, in presence of two witnesses.

ALOYS HAGE.
